UNITED STATES PATENT OFFICE.

MICHAEL J. MANAHAN, OF INDIANAPOLIS, INDIANA.

DOOR AND WINDOW SHADE AND CURTAIN CLAMP.

Application filed February 21, 1922. Serial No. 538,325.

To all whom it may concern:

Be it known that I, MICHAEL J. MANAHAN, a citizen of the United States, residing at Indianapolis, in the county of Marion and 5 State of Indiana, have invented new and useful Improvements in Door and Window Shade and Curtain Clamps, of which the following is a specification.

The object of this invention is to provide 10 means for supporting shade-rollers and curtains over the glass of doors of usual construction, on French-doors and French-windows, and on windows with vertically movable sash, without marring the face of the 15 woodwork by driving nails or screws into their finished surfaces.

The object is to make the attachment to 20 the edges instead of to the faces of the door or window, or their frames, in a secure and simple manner subject to easy and quick application of the holding device and its removal.

I accomplish the above, and other objects 25 which will hereinafter appear, by the means illustrated in the accompanying drawing, in which—

Fig. 1, is a perspective view of my invention as applied to a door or window, or to 30 a window frame. Fig. 2, is a cross-section of the extension bar and end view of the curtain supporting bar and socket support for the latter. Fig. 3, is a view in cross-section of the extension bar, and an inner side-elevation of the shade-roller arm. Fig. 4, is a 35 side-elevation and partial section of the pawl and rack mechanism for adjusting the members of the two-part extension-bar relative to each other. Fig. 5 is a cross-section of the extension-bar showing the gripping 40 bolt securing the bar to the woodwork. Fig. 6, is a cross-section through the two lapped members of the extension-bar. Fig. 7, is a perspective view and partial longitudinal section of a modified form of curtain 45 rod, and Fig. 8 is a modified means for adjusting the two parts of the extension bar.

Like characters of reference indicate like parts in the several views of the drawing.

My invention consists primarily of a pair 50 of rods, here shown as angle-bars 9 and 10 made of angular material for additional stiffness and strength, held slidably together by a loop 11, at the inner end of rod 9, and also secured together by a pair of 55 standards 12 attached to the inner end of

the rod 10. The standards are joined under both rods at their lower ends, and between them a lever 13 is pivoted, having a single tooth which is adapted to engage with teeth formed in the upper edge of bar 60 9, and to move the two rods relative to each other to increase their combined lengths when the lever is lowered into contact with the rods as shown in Figs. 1 and 4. Mounted on the same pivot with lever 13 is an oscillating double-ended pawl 14, the ends of which are adapted to be brought alternately into engagement with the teeth of the bar to prevent back movement of either of the rods and consequent shortening of their combined lengths. In the top of lever 13 are 65 the notches 16, in an appropriate one of which a pawl 17 enters to hold the lever down against the expansion rods. The pawl has an extension 18 by which it is released from engagement with the lever.

Passing transversely through the bars 9 and 10, beyond their lapped portions, are the respective gripping bolts 20, each having a sharp-edged head 21. The bolts are 80 projected into a recess of the room caused by the thickness of the door, window, or their casing, and their heads 21 are forced into the adjacent edges of the woodwork by moving the lever 13 to increase the combined length of the rods 9 and 10, thus holding them in position. A series of holes may be provided for changing the distance from the middle of the rod, of the bolts.

Shade-roller arms 23 and 24, with the 85 usual opening for receiving and holding the shade-roller pins, and having their inner portions bent at right angles to their bodies for substantial bearing against the casing, are provided with holes through 90 which the respective rods 9 and 10 are passed so the arms are slidably mounted on the rod. Undue looseness is avoided by leaf-springs 25, which are riveted to the arms and bear frictionally against the rods. 100 The arms are provided with loops, shown in dotted lines 29, Fig. 3, for supporting curtain rods between the shade and glass on doors and the like.

Curtain-supporting rods 26 and 27, here 105 shown as flat bars turned-edge up and with rounded ends bent to form vertical hooks, are supported by members 30, formed of strap metal bent U-shape and slotted, for sliding movement on their respective rods 9 110

and 10, which have their ends bent to form sockets that receive and hold the end-hooks of rods 26 and 27.

The members 30, and the arms 23 and 24, are slidable on their supporting-rods to exact positions, after the latter are placed, and secured, in their final positions.

The application and use of my invention will be apparent from the foregoing description. It can be applied to any door or window or to their casings, although the latter have projecting molds, and where the construction makes it desirable to do so, the outer-ends of the rods 9 and 10, which have barbs 33 for the purpose, may be pressed into holding engagement without using the gripping bolts 20.

In the modification shown in Fig. 7, a cylindrical rod 34 has solid ends 35 telescoping therein. The ends 35 are bent and are inserted in the sockets 30. In the modification shown in Fig. 8, a pinion 36 engages with the teeth on rod 9, as a substitute for the toothed-lever shown in Fig. 4.

While I have here shown the best form of my invention now known to me, it is obvious that many modifications are possible without departing from the spirit of my invention, some of which have been herein described, and I therefore do not desire to be held to the construction shown, any more than is required by the appended claims, and having thus fully described my invention what I claim as new and wish to secure by Letters Patent is—

1. A shade and curtain supporter comprising a pair of rods movable longitudinally of each other, one of said rods having a row of teeth, a pivoted lever on the other rod having a tooth engaging with the teeth on the first rod, a pawl and ratchet means for holding a given position of the

lever said pawl having an extension by which it is released from the lever, means on the rods to enter the wood work by increase in the length of the device by a relative movement of the two rods, and shade-and-curtain holding means on the rod. 45

2. A shade and curtain supporter comprising a pair of rods movable longitudinally of each other, one of the rods having a row of teeth, a lever pivoted on the other rod having a member engaging with the teeth on the first rod, adjustable means pivoted on the same pivot as the lever to prevent shortening of the combined length of the bar by engaging with the teeth of the toothed rod, means on the rod to enter the wood by increase in the length of the device by a relative movement of the two rods, and shade-and-curtain holding means on the rods. 50 55

3. A shade and curtain supporter comprising a pair of rods movable longitudinally of each other, one of the rods having a row of teeth, a pivoted lever on the other rod having a member engaging with the teeth on the first rod, an oscillating double-ended pawl mounted on the same pivot as the lever, the ends of which are adapted to be brought alternately into engagement with the teeth of the bar to prevent back movement of either of the rods and consequent shortening of their combined lengths, means for holding a given position of the lever, means on the rods to enter the wood-work by increase in the length of the device by a relative movement of the two rods, and shade - and - curtain holding means on the rod. 60 65 70 75 80

Signed at Indianapolis, Indiana, this the 20th day of February, 1922.

MICHAEL J. MANAHAN.
